UNITED STATES PATENT OFFICE

MASAO HASEGAWA, OF SANTA ROSA, CALIFORNIA

CIRCUIT-CONTROLLING DEVICE

Application filed June 30, 1928. Serial No. 289,372.

My invention relates to improvements in direction indicators, and it consists in the combinations, constructions and arrangements hereinafter described and claimed.

5 This invention is an improvement over the device shown in my co-pending application, Serial No. 177,076 filed March 21, 1927. In the co-pending application I set forth a pair of switches which are held in 10 operative position when manually actuated, these switches closing circuits to direction-indicating lights and keeping the circuits closed so long as the front wheels of the car remain turned for causing the car to either turn to the right or to the left. 15 Special mechanism operatively connected to the steering mechanism is shown in my co-pending application for automatically opening the switches when the front wheels are 20 straightened out.

The present invention shows an improvement in the mechanism actuated by the steering apparatus of the automobile.

A further object of my invention is to 25 provide a more simplified means for de-energizing the magnets which hold the switches in operative position after they have once been moved. This means is operated when the wheels are straightened 30 out.

Other objects and advantages will appear as the specification proceeds, and the novel features will be particularly pointed out in what I hereinafter claim.

35 My invention is illustrated in the accompanying drawing forming a part of this application, in which

Figure 1 is a schematic view showing the switches electrically connected to the signal lights and the releasing mechanism;

40 Figure 2 is an enlarged view of the releasing mechanism, a portion of the front wall being broken away for clarity; and

Figure 3 is a section along the line 3—3 45 of Figure 2.

In carrying out my invention, I make use of an automobile indicated generally at 1. Upon the four fenders of the automobile I mount direction-indicating lights 2—2 and 3—3 (see Figure 1). These lights are electrically connected to each other and to manually-controlled switches of a construction now to be described.

50 In Figure 1 I show a support 4 which may be disposed in the driver's compartment at a point near the driver. The support carries a lever 5 which is pivoted at 6. Push buttons 7 and 8 are disposed at the extremities of the lever, and directly below these push buttons I mount conductor plates 55 9 and 10 that are insulated from each other. Springs 11 and 12 tend to swing the lever 60 5 back into the position shown in Figure 1.

The conductor plate 9 contacts with plates 13 and 14 when the push button 65 7 is depressed, while the plate 10 contacts with plates 15 and 16. A wire 17 passes from the plate 14 and is wound around a magnet 18. In like manner a wire 19 is passed around a magnet 20 and is connected to the terminal 70 15. The wires 17 and 19 merge into a common wire 21 which leads to a binding post or terminal block 22 mounted in a release mechanism indicated generally at 23. The terminal 13 is connected to the lights 3—3 75 by a wire 24, and in like manner the terminal 16 is connected to lights 2—2 by a wire 25. The lights 2—2 and 3—3 are grounded as at 26 and 27.

80 Referring to Figure 2, it will be noted that the binding post 22 normally contacts with a conductor strip 28 carried by an arm 29, the latter being urged toward the binding post 22 by means of a spring 30. A wire 31 leads from the conductor strip 28 to a magnet 32, and the magnet is grounded at 33 for completing the electric circuit. A lever 34 is pivoted at 35 and swings independently of the arm 29. This lever carries at its lower end an adjustable permanent 85 90 magnet 36.

hard steel magnet 36 that is adapted to be attracted by the magnet 32 when the latter is energized.

The upper end of the lever 34 is pivoted to an L-shaped arm 37 at 38. This arm carries a spring hinge 39 which permits a trigger 40 to swing in one direction without affecting the movement of the arm and which cannot swing in the opposite direction, and therefore a movement of this trigger in the latter direction will swing the arm. The trigger 40 is positioned adjacent to a drum indicated generally at 41, and the trigger is normally spaced away from projections 42 forming a part of the drum.

The drum is rotatably carried by the supporting plates 43 of the release mechanism 23. A spring 44 tends to rotate the drum in one direction. The drum has an annular groove 45 for receiving a cable 46. One end of the cable is connected to the drum while the other end is passed by the idler pulleys 47 and then connected to an arm 48.

In Figure 1 I show the arm 48 as being connected by a link 49 to an arm 50 that forms a standard part of an automobile steering mechanism. It will be seen from this construction that a swinging of the arm 50 in either direction will rotate the drum 41 in the same direction and against the tension of the spring 44.

From the foregoing description of the various parts of the device, the operation thereof may be readily understood.

The push button 8 when depressed illuminates the signals on the right-hand side of the car, while the push button 7 illuminates the signals 3-3. Assume that the driver is going to turn to the right. He depresses push button 8, which causes a current to flow from a battery 51 through wires 52 and 53 to the contact plate 10. From this point the current flows to the lights 2-2 and through the magnet 20 to the binding post 22. The binding post is in electrical connection with the conductor strip 28, and therefore the current will flow through the magnet 32, energize the latter, and cause it to attract the permanent magnet 36. This will cause the lever 34 to swing in a clockwise direction about the pivot 35 and to bring the trigger 40 into a position where it will be engaged by the projections 42.

The driver in turning the steering wheel to the right swings the arm 50, which in turn will rotate the drum 41 against the tension of the spring 44 and cause the projections 42 to pass by the trigger 40 in a counter-clockwise direction. The trigger will merely be swung about its spring hinge 39 and will not affect the movement of the arm 37. It will therefore be seen that the lights 2-2 will remain illuminated continuously from the time the push button 8 is de-

pressed, and that the initial turning of the front wheels will have no effect upon the releasing mechanism.

After the driver has made the turn and starts to straighten out his car, the arm 50 is moved in the opposite direction and feeds slack into the cable 46. This permits the spring 44 to rotate the drum 41 in a clockwise direction. The projections 42 will strike the trigger 40 and will cause the trigger to swing the arm 37 in an anti-clockwise direction about the point 38 as a pivot. This movement causes the end 34 of the arm 37 to move the conductor strip 28 away from the binding post 22 and to temporarily open the circuit. This de-energizes the magnets 20 and 32 and permits the springs 12 and 55 to return the levers 5 and 34 back into normal position. Of course, the arm 37 will return to the position shown in Figure 2 as soon as the projection 42 that has tripped the arm passes by the trigger 40. This permits the spring 30 to return the conductor strip 28 into contact with the binding post 22, and the device is ready for another operation. It might be advisable to place a spring 56 between the arm 37 and the wall 43, this spring being strong enough to swing the arm back into the position shown in Figure 2, yet at the same time permitting a movement of the arm to the right when the latter is carried into engagement with the projections 42, by the lever 34. The spring is not strong enough to cause the arm 37 to move the conductor strip 28 out of contact with the binding post 22.

Although I have shown and described one embodiment of my invention, it is to be understood that the same is susceptible of various changes, and I reserve the right to employ such changes as may come within the scope of the invention as claimed.

I claim:

1. In a circuit controlling device, a circuit breaker, a drum for actuating said circuit breaker when said drum is moved in one direction, means for moving said drum in the opposite direction and including an arm, a cable secured to said arm and being passed between two guide rollers and then secured to the drum, said guide rollers being disposed adjacent to said arm when the latter is in normal position, means connecting said arm with the steering mechanism of a vehicle for swinging said arm, when the steering mechanism is actuated, said arm having a one way acting pawl for causing said drum to rotate in one direction regardless in which direction the arm is swung, spring means for returning the drum to normal position, and means actuated by the drum only when the latter is moved by the spring for opening the circuit breaker.

2. In a circuit controlling device, the com.

bination with a bell crank, of a steering mechanism for a vehicle, an arm, a link positively connecting the arm with the bell crank, a drum, a cable connecting the drum with the arm, means including a one way acting pawl and associated with the cable for causing the pawl to rotate the drum in the same direction whether the arm is moved in either one of two directions, spring means for returning the drum back to normal position, and a circuit breaker actuated by said drum when the latter is rotated by said spring.
